Fig. 11

FIGURE 1 is a perspective view of a boat showing my new design;

FIGURE 2 is an elevational view of the side opposite that shown in FIGURE 1;

FIGURE 3 is a top plan view thereof;

FIGURE 4 is a front elevational view thereof;

FIGURE 5 is a rear elevational view thereof;

FIGURE 6 is a perspective view of a modified form of the boat shown in FIGURE 1;

FIGURE 7 is an elevational view of the side opposite that shown in FIGURE 6;

FIGURE 8 is a top plan view of the boat shown in FIGURE 6;

FIGURE 9 is a front elevational view of the boat shown in FIGURE 6;

FIGURE 10 is a rear elevational view of the boat shown in FIGURE 6; and

FIGURE 11 is a bottom plan view of the boat shown

in FIGURES 1 and 6.

The dominant features of my design reside in the portions shown in full lines. The top shown in broken lines in FIGS. 1 and 6 has been omitted from FIGS. 3, 5, 8 and 10 and the rear seats have been omitted from FIG. 6 for clarity of illustration.

I claim:

The ornamental design for a boat, as shown and described.
